UNITED STATES PATENT OFFICE.

HENRY BUSSE, OF WILLIAMSPORT, PENNSYLVANIA, ASSIGNOR TO CHARLES R. HARRIS, OF SAME PLACE.

DESIGN FOR A BICYCLE-FRAME.

SPECIFICATION forming part of Design No. 27,186, dated June 8, 1897.

Application filed April 14, 1897. Serial No. 632,184. Term of patent 14 years.

To all whom it may concern:

Be it known that I, HENRY BUSSE, a citizen of the United States, residing at Williamsport, in the county of Lycoming and State of Pennsylvania, have invented and produced a new and original Design for Bicycle-Frames, of which the following is a specification, reference being had to the accompanying drawing, forming a part thereof.

10 The accompanying drawing illustrates my design.

The leading feature of my design consists of a bicycle-frame having a circular rear portion having a rear-wheel bearing eccentrically located therein and a connecting-bar extending forward from the top of this circular rear portion.

15 A represents the steering-head, and B is the frame. The frame consists in the main

of a tube or bar 1, extending from the steering-head rearward and downward and then around in the form of a circle, having a bearing 3 between the parts of the frame for a sprocket-wheel and terminating in a bearing 4 within the circle for the rear axle. It also 25 consists in a bar or tube 5, extending straight rearward from the upper end of the steering-head to the top of the circular rear portion of the frame and terminating in an upturned seat-post at its rear end. 30

What I claim is—

The design for bicycle-frames substantially as herein shown and described.

HENRY BUSSE.
